WORK HOLDER

John J. Groden, Philadelphia, Pa.

Application September 1, 1938, Serial No. 227,875

11 Claims. (Cl. 175—367)

This invention has to do with work holders such as are commonly employed on machine tools for the purpose of holding work that is being operated upon. The invention is concerned primarily with work holders of the magnetic type.

The invention has in view, as its foremost objective, the provision of a magnetic work holder which is characterized by the presence of permanent magnets. When permanent magnets are employed it is impossible to control the magnetic force by controlling an electrical current, as in those cases in which the magnetic force is generated by electrical current. Hence two important conditions are presented which must be adequately accommodated in order to provide a work holder that is usable under practical conditions.

One of these conditions is the necessity for making provision for accurately truing up the work on the holder, and this is particularly important when the machine tool is of the rotary type, such as a lathe or grinder. Another factor is that of easy removal of the work from the holder.

With the foregoing conditions in mind the invention has in view, as a further detailed object, the provision of a work holder including permanent magnets together with means for diminishing the effects of the magnets as occasion demands.

More in detail this invention has in view, as an object, the provision of a work holder including a face plate against which the work is adapted to engage, and with which face plate is associated a magnet assembly that is movable with respect thereto. When the magnetic assembly is spaced away from the plate the magnetic force effective at the surface of the plate is greatly diminished as compared to the condition in which the magnetic assembly is in close juxtaposition to the face plate.

Another somewhat more detailed object of the invention is the provision of means which are operable under the principles of mechanical advantage for moving the magnetic assembly with respect to the face plate. Other more detailed objects and advantages of the invention are associated with the provision of mechanism in the attainment of this objective.

Another important feature of the present invention is the actual construction of the face plate and the magnet assembly. It is an object of this invention to provide a magnet assembly in which a plurality of horseshoe magnets are included. These horseshoe magnets are em-

bedded in a non-magnetic material such as an appropriate aluminum alloy. The face plate is rendered of a construction corresponding to the arrangement of horseshoe magnets in the magnetic assembly, the construction including essentially a plurality of pieces of magnetic material such as iron or steel that are arranged to constitute continuations of the horseshoe magnets, and are maintained in spaced relationship by being embedded in non-magnetic material.

Other more detailed objects and advantages will in part become apparent and in part be hereinafter stated, as the description of the invention proceeds.

The invention, therefore, comprises a work holder characterized by the presence of permanent magnets which are included in a magnet assembly that is movable with respect to a face plate against which the work engages. Appropriate mechanism for moving the magnetic assembly with respect to the face plate under the principles of mechanical advantage is also provided. The particular construction of the face plate and magnet assembly is also an important part of the invention.

For a full and more complete understanding of the invention reference may be had to the following description and accompanying drawing, wherein

Figure 1 is a section through a work holder made in accordance with the precepts of this invention,

Figure 2 is a perspective view of the magnet assembly and face plate with the latter broken away, and

Figure 3 is a bottom plan view of the gear mechanism for causing movement of the magnet assembly.

Referring now to the drawing, wherein like reference characters denote corresponding parts, and more particularly to Figure 2, the magnet assembly is referred to in its entirety by the reference character M. This magnet assembly M comprises a plurality of horseshoe magnets 10 (see Figure 1) which are made from a good material having permanent magnetic properties such as iron.

In constructing the magnet assembly M the required number of permanent horseshoe magnets 10 are placed in a mold together with a sleeve 11 (see Figure 1) which is provided with large exterior screw threads, as shown at 12. A non-magnetic material such as an appropriate aluminum alloy is then cast about the magnets 10 and into the interior of the sleeve 11.

In this connection it is noted that the sleeve 11, which constitutes the shank of the magnet assembly M, is formed with a bore 13 which is enlarged at 14 to define a shoulder 15. Thus with the aluminum alloy, designated 16, cast into the interior of the bore 13 of this sleeve 11, the shoulder at 15 insures of strong structural effects.

The face plate of the holder is referred to in its entirety by the reference character F, and is shown as consisting of a circular plate construction 17 that is carried at the forward end of a cylindrical member 18 having a smooth inner cylindrical bore 19 complementary to the cylindrical surface 20 on the magnet assembly M. This plate 17 is preferably removably held in the cylindrical member 18.

The circular plate structure 17 comprises a plurality of pieces 21 of material having good magnetic properties, such as iron, which pieces are embedded in a body structure of a non-magnetic material such as an aluminum alloy as designated at 22, and arranged to constitute substantial continuations of the horseshoe magnets 10.

As shown in Figure 2, the ends of the horseshoe magnets 10 lie flush in the face of the magnetic assembly M, as shown at 23, and when the magnetic assembly M is in engagement with the face plate F the pieces 21 are intended to be in substantial alignment with the ends 23. With the plate structure 17 removable, the size and shape of the pieces 21 of magnetic material may be varied as occasion demands.

The cylindrical member 18 may be provided with means for permitting the same to be gripped by a spanner wrench, such as the openings shown at 24. At its inner free edge this cylindrical member 18 is reduced in thickness and the exterior surface thereof provided with screw threads, as indicated at 25.

A gear carrying member 26 is of a cylindrical formation corresponding to the member 18 and is interiorly threaded, as shown at 27, with the latter threads engaging the threads 25 to maintain the members 18 and 26 in assembled relationship.

Extending inwardly from the cylindrical wall of the carrier 26 is a horizontal flange structure 28 that constitutes an abutment for limiting movement of the magnetic assembly M in one direction, the latter being adapted to engage thereagainst.

Disposed within the carrier 26 is a sleeve-like screw member 29 having a bore at 30 which is formed with threads 31 that are complementary to the threads 12 on the sleeve 11 and in mesh therewith. This sleeve 29 terminates in an outturned flange 32 that engages the flange 28. The outer peripheral edge of the flange 32 is formed with a series of gear teeth defining a circular rack 33, the latter being slightly inclined, as shown in the lower part of Figure 1 so as to properly engage with the beveled gears or pinions 34.

Each of the pinions 34 is carried by a shaft 35 that has wrench engaging means in the form of a noncircular socket 36 at one end, and which shaft has bearing in an opening 37 formed in the wall of the carrier 26. At the other side of the pinion 34 the shaft 35 is reduced, as shown at 38, and has bearing in an opening 39 formed in a sleeve 40 that is carried by the work holder 26 and engages the screw sleeve 29.

This sleeve 40 may be integrally formed with an end piece shown at 41 that is secured to the

carrier part 26 by bolts 42. A plate shown at 43 may be anchored to this end piece 41, as by headed bolts shown at 44, and this plate 43 is adapted to be mounted on a lathe or other machine tool.

As shown clearly in Figure 2, the threads 12 are interrupted to provide a key-way 45, and received in this key-way 45 is a lug 46 that is carried by the flange 28. The reception of the lug 46 in the key-way 45 serves to hold the sleeve 11 against rotation.

The mode of usage of the above specified work holder may be described by noting that when the work is first to be positioned against the face plate F the magnet assembly M will assume the retracted position shown in Figure 1. Under this condition there is some slight magnetic force evidenced at the surfaces of the pieces 21, but this force may be readily overcome, and under this condition work may be accurately trued on the face plate F. A wrench is then inserted in any one of the sockets 36 which may be convenient, and upon the turning thereof the pinion 34 is rotated to turn the flange 32 and screw sleeve 29.

As the threads 31 carried by the latter are in mesh with the threads 12, and because of the engagement of the key 46 in the key-way 45, which holds the sleeve 11 against rotation, the interengagement of the threads 31 and 12 moves the magnetic assembly M outwardly until the ends 23 of the magnets 10 engage the underfaces of the pieces 21 in the face plate F. The full effect of the permanent magnets 10 is now evidenced on the work and the latter is firmly held against the face plate F for the operations which may be performed thereon.

When these operations are completed it is, of course, desirable to remove the work from the work holder. With the strong magnetic force evidenced by the close juxtaposition of the magnet assembly M to the face plate F considerable difficulty would be experienced upon removing the work. However, upon again inserting a wrench in one of the sockets 36, and turning the latter, principles of mechanical advantage are brought into play so that the magnet assembly M is readily retracted from the face plate F, and when the flange 28 is abutted this magnetic force is so minimized as to render the removal of the work an easy proposition.

It is to be understood that the invention is not to be limited to any particular number or size of magnets, nor to the particular type of gear mechanism illustrated, as various modifications of these and other details might be carried out in putting the invention into practice within the purview of the appended claims.

I claim:

1. A work holder of the character described comprising a magnet assembly including a plurality of permanent magnets of the horseshoe type, the ends of said magnets lying substantially in the face of said magnet assembly, a face plate including pieces of magnetic material with pieces of non-magnetic material interposed therebetween, structure for associating said face plate with said magnet assembly so that said pieces of magnetic material in the face plate constitute continuations of the ends of said horseshoe magnets, and mechanism for moving said magnet assembly toward and away from said face plate.

2. A work holder of the character described comprising a cylindrical member having a bore, a face plate carried by said cylindrical member at

- one end, a magnet assembly of cylindrical formation slidably received in said bore, a plurality of magnets included in said magnet assembly, a shank extending from said magnet assembly, 5 screw threads on said shank, a screw sleeve having threads in engagement with said threads on the shank, and mechanism for causing rotation of said screw sleeve to move said shank and magnet assembly.
- 10 3. A work holder of the character described comprising a cylindrical member having a bore, a face plate carried by said cylindrical member at one end, a magnet assembly of cylindrical formation slidably received in said bore, a plurality of magnets included in said magnet assembly, a shaft extending from said magnet assembly, screw threads on said shank, a screw sleeve having threads in engagement with said threads on the shank, means for holding said magnet assembly against rotation with respect to said cylindrical member, and gear mechanism for rotating said screw sleeve.
- 15 4. A work holder of the character described comprising a cylindrical member having a bore, a face plate carried by said cylindrical member at one end, a magnet assembly of cylindrical formation slidably received in said bore, a plurality of magnets included in said magnet assembly, a shank extending from said magnet assembly, screw threads on said shank, a screw sleeve having threads in engagement with said threads on the shank, an outwardly extending flange carried by said screw sleeve, a circular rack formed on a face of said outwardly extending flange, a pinion in engagement with said rack, and means for rotating said pinion.
- 20 5. A work holder of the character described comprising a cylindrical member formed with a bore and having a face plate at one end, said face plate including pieces of magnetic material maintained in spaced relationship by being embedded in a main body portion of non-magnetic material, a magnet assembly of cylindrical formation slidably received in said bore, said magnet assembly consisting of a main body portion of non-magnetic material in which are embedded a plurality of permanent horseshoe magnets, a shank on said magnet assembly, screw threads on said shank, said screw threads being formed with a key-way, a carrier structure connected to said cylindrical member, an inwardly extending flange formed on said carrier structure, a lug on said flange received in said key-way, a screw sleeve having threads in engagement with the said threads on the said shank, an outwardly extending flange carried by said screw sleeve, a circular rack formed on a face of said outwardly extending flange, pinions carried by said carrier structure and engaging said rack, and means for rotating said pinions.
- 25 6. A work holder of the character described comprising a cylindrical member formed with a cylindrical bore, a face plate removably carried by said cylindrical member at one end, said face plate including a plurality of pieces of magnetic material embedded in a main body structure of non-magnetic material and maintained in spaced relation therein, a magnet assembly of cylindrical formation movable in said bore, a plurality of permanent magnets included in said magnet assembly and having ends in substantial alignment with the magnetic pieces in the face plate, and means for moving said magnet assembly toward and away from said face plate.
- 30 7. A work holder of the character described comprising a magnet assembly including at least one permanent magnet, a face plate for engaging work and transmitting magnetic lines of force from said magnet assembly through said work, and mechanism for making and holding adjustments between said magnet assembly and face plate intermediate limits of movement between said magnet assembly and face plate.
- 35 8. A work holder of the character described comprising a carrier member formed with a bore, means substantially coaxial with said bore for mounting the carrier member on a machine tool, a face plate closing said bore and including pieces of magnetic material, a magnet assembly including a plurality of permanent magnets in said bore and movable therein, and mechanism for adjusting and holding in any adjusted position said magnet assembly within said bore, said mechanism being operable from the side of said carrier member.
- 40 9. A work holder of the character described comprising work piece engaging means, a piece of metal of high magnetic permeability in said work piece engaging means, a magnet assembly including a magnet constructed and arranged to generate a magnetic flux in the direction of said work piece engaging means only, and means operating centrally of said magnet assembly for adjusting the distance between said magnet assembly and said work piece engaging means.
- 45 10. A work holder of the character described comprising work piece engaging means, a plurality of pieces of metal of high magnetic permeability in said work piece engaging means, a magnet assembly including a plurality of permanent magnets having poles substantially in alignment with said pieces of metal, said magnet assembly being constructed and arranged to generate a magnetic flux in the direction of said work piece engaging means only, and means for adjusting and maintaining alignment between said magnet assembly and said work piece engaging means.
- 50 11. In a work holder of the character described, a magnet assembly including a plurality of permanent magnets embedded in a main body portion of a non-magnetic material, a face plate for engaging work and transmitting magnetic lines of force from said magnet assembly through said work, a shank carried by and disposed centrally on said magnet assembly, screw threads on the exterior of said shank, and means cooperating with the screw threads for making and holding adjustments between said magnet assembly and face plate intermediate limits of movement between said magnet assembly and face plate.

JOHN J. GRODEEN.
